UNITED STATES PATENT OFFICE

2,028,978

MATRIX AND METHOD OF MANUFACTURING THE SAME

Arthur H. Hedly, Chicago, Ill., assignor to Ludlow Typograph Company, Chicago, Ill., a corporation of Illinois

Application November 5, 1934, Serial No. 751,630

15 Claims. (Cl. 101—401.2)

My invention relates more especially to matrices used in the production of printing-face-equipped bodies, particularly, though not exclusively, line slugs and involving in the manufacture thereof, the formation of the matrices by forcing into matrix blanks, as for example and commonly of brass, punches provided with punch surfaces conforming to the forms of type faces to be cast in the matrices.

10 Considerable difficulty has been experienced in the commercial production of driven matrices formed from matrix blanks of the desired hard material, commonly brass, due to the reluctance to flow of the metal of the matrix blank into the counters or grooves of the punch, particularly when such counters or grooves are relatively narrow and deep, resulting in the printing faces of the bodies, cast from said matrices, presenting such low height shallow counters, that ink received therein will transfer to the paper in the printing operation and produce an imperfect printing impression.

20 My object is to overcome the objection above set forth and provide for the production of counters or ribs on the matrices of such height as to insure against the transfer to the paper of ink from the counters or grooves in the printing face portions of the printing-face-equipped bodies made from the matrices, even where these counters are relatively narrow, while permitting of the manufacture of the bodies of the matrices including the portions thereof in which the matrix-cavities are to be formed, of desirable non-corrodable metal, as for example brass commonly used 25 in the production of type matrices and which is of sufficient hardness to withstand abuse in handling.

25 Referring to the accompanying drawings:

Figure 1 is a broken plan view of matrix-blank holding mechanism which may be used for holding the blank during the driving operation.

Figure 2 is a broken sectional view taken at the irregular line 2—2 on Fig. 1 and viewed in the direction of the arrow.

Figure 3 is a face view of one form of matrix embodying my invention and produced in accordance with my invention.

Figure 4 is a section taken at the line 4—4 on Fig. 3 and viewed in the direction of the arrows.

Figure 5 is a view like Fig. 3 of another embodiment of the invention and produced in accordance with my method.

Figure 6 is a section taken at the line 6—6 on Fig. 5 and viewed in the direction of the arrows.

Figure 7 is a view like Fig. 3 of another em-

bodiment of the invention and produced in accordance with my method.

Figure 8 is an end view of the matrix of Fig. 7.

Figure 9 is a bottom plan view of another embodiment of the invention and produced in accordance with my method.

Figure 10 is an edge view of the matrix of Fig. 9.

Figure 11 is a bottom plan view of still another embodiment of the invention and produced in accordance with my method; and

Figure 12, a section taken at the line 12—12 on Fig. 11 and viewed in the direction of the arrows.

In accordance with my invention the body of the matrix blank, and including the portion thereof in which the matrix cavity is to be formed, is made of such metal as to be suitable for the driving therein of the matrix cavity and the molding in this cavity of type metal, and be capable of withstanding abuse in handling, it being preferred that the metal used be brass as now commonly used for the making of matrix blanks; and the part of the blank presenting the counter-forming portion, or portions, and provided as a relatively thin section, backed by harder metal, such as for example steel, forming an anvil resulting in such enforced augmented flow of the softer metal of the blank into the counter portions of the punch in the operation of driving the matrix cavity, as to insure the forming of the desired high counters in the matrix cavity.

According to the embodiment of the invention shown in Figs. 3 and 4 which illustrate a matrix for the casting of a capital M having sharp counters 12, the body of the matrix blank from which the matrix referred to is formed, is provided with a recess 13 in the form of a bore extending from side to side thereof, as represented, to cause the blank to present a relatively thin web section 14 extending along the center of the matrix blank, the recess 13 containing a closely-fitting round bar 15 of metal harder than the body of the matrix blank, as for example steel, which extends throughout substantially the full length of the recess 13 and forms an anvil functioning in the driving operation as above stated.

In the embodiment of the invention illustrated in Figs. 5 and 6 wherein a matrix for casting a capital B is illustrated having small counters represented at 16, the body of the matrix blank from which the matrix shown is formed is provided with a recess 17 in the form of a bore extending from end to end thereof as represented to cause the blank to present a relatively thin web section 18 extending along the center of the matrix, the

recess 17 containing a closely fitting round bar 19 of metal harder than the body of the metal of the matrix blank, as for example steel, which extends throughout substantially the full length of the recess and forms an anvil in the driving operation.

5 In the embodiment of the invention illustrated in Figs. 7 and 8, wherein a matrix for casting a capital W is provided having narrow counters 20 extending over a large area, the body of the matrix blank, is provided with two parallel recesses 21 10 in the form of bores extending from end to end of the matrix blank, these recesses containing closely fitting round bars 22 of metal harder than the body of the matrix blank, as for example steel, the provision of the recesses 21 as stated causing 15 the matrix blank to present relatively thin web-like sections on which portions of the counters 20 are formed and the bars 22 serving to anvil function in the driving operation.

20 The embodiment of the invention illustrated in Figs. 9 and 10 contemplates the forming of the body portion of the matrix blank, with a recess 23 in its back surface, in the form of a groove, or channel, thereby providing a relatively thin web section 24 in which the matrix cavity is produced; 25 and locating in the recess 23 a block 25 of harder metal than the metal of which the body portion of the matrix blank is formed, as for example steel, which functions as an anvil in the matrix- 30 driving operation.

30 In accordance with the embodiment of the invention shown in Figs. 11 and 12 the body of the matrix blank is annularly recessed at its back surface, as represented at 26, to cause the matrix- 35 cavity-forming portion of the matrix to be in the form of a thin web 27, the recess 26 containing a circular block 28 functioning as in the case of the block 25 of Figs. 9 and 10.

40 It is necessary that the matrix blank, in the punching operation, be confined against lateral and downward deformation at its side and bottom surfaces, respectively. This may be accomplished in any desirable way as for example by the means shown in Figs. 1 and 2 which are of a construction well known in the art, and therefore a brief description thereof will suffice.

45 The mechanism shown comprises a bed 29 superposed by a block 30 rigidly secured thereto as by screws, this block having one corner thereof recessed as represented at 31, the walls of this recess and represented at 32 and 33 extending at a right angle to each other and being lined with bars 34 and 35, the block 30, lined as stated, constituting one jaw of a chuck in which the matrix blank is to be held. The other jaw of this chuck, 50 represented at 36 and formed with an apex portion 37, is guidingly confined at its outer end in parallel guides 38, so disposed that the jaw is movable from the closed position shown in Fig. 1, 55 into open position, and vice versa.

60 The extreme apex portion 37 of the jaw 36 contains a recess 39, the side wall 40 of which is parallel with the inner face of the plate 34, the recess 39 containing a block 41 held in place by a screw device 42, the outer face 43 of the block 41 being parallel with the inner face of the bar 35. There is thus provided between the bars 34 and 35, the wall 40 and face 43 of the block 41, a recess 44 in which the matrix blank herein represented at 45, is located.

70 The bottom of the matrix blank rests upon a rigid foundation which, in the case of the particular machine shown, is a hardened steel plate 46 carried on the upper face of the matrix ejector 75 47 slidably mounted in the bed 29 of the machine.

this ejector, in the operation of producing the matrix cavity extending into the position shown in Fig. 2.

In the operation of the mechanism shown the jaw 36 is withdrawn from the position shown in Fig. 1 to permit of the introduction of the blank 45 into the recess 44 and the jaw 36 thereupon forced inwardly to the position shown in Fig. 1 by any suitable mechanism as for example by pneumatic mechanism (not shown), to firmly 10 clamp the blank 45, the side walls of the recess 44 and the portion of the machine upon which the blank rests serving to prevent free lateral and downward flow of the metal of the matrix blank in the operation of forcing the punch into it to 15 form the matrix cavity.

While I have illustrated and described certain ways in which my improved method may be practiced and certain embodiments of my invention, I do not wish to be understood as intending to limit 20 it thereto as the method may be practiced in other ways and the constructions shown variously modified and altered, without departing from the spirit of my invention.

What I claim as new, and desire to secure by 25 Letters Patent, is:

1. The method of forming matrices which consists in providing a metal matrix body the portion thereof in which the matrix cavity is to be formed comprising a relatively thin web section 30 forming a portion only of said body, backing said web-section with material harder than that forming said body, and forcing a matrix-forming punch against said portion to form the matrix cavity therein.

35 2. The method of forming matrices which consists in providing a metal matrix body recessed between its upper and lower surfaces adjacent the portion thereof in which the matrix cavity is to be formed to cause said portion to comprise 40 a relatively thin web section, providing in the recess in said body backing for said web-section comprising material harder than that forming said body, and forcing a matrix-forming punch against said portion to form the matrix cavity 45 therein.

50 3. The method of forming matrices which consists in providing a metal matrix body, recessing said body between its upper and lower surfaces adjacent the portion thereof in which the matrix cavity is to be formed to cause said portion to comprise 55 a relatively thin web section, providing in the recessed portion of said body backing for said web-section comprising material harder than that forming said body, and forcing a matrix-forming punch against said portion to form the matrix cavity therein.

60 4. The method of forming matrices which consists in providing a metal matrix body, boring said body between its upper and lower surfaces adjacent the portion thereof in which the matrix cavity is to be formed to cause said portion to comprise 65 a relatively thin web section, providing in the bored portion of said body backing for said web-section comprising material harder than that forming said body, and forcing a matrix-forming punch against said portion to form the matrix cavity therein.

70 5. The method of forming matrices which consists in providing a metal matrix body having 75 substantially parallel recesses between its upper and lower surfaces adjacent the portion thereof in which the matrix cavity is to be formed to cause said portion to comprise a relatively thin web-section, providing in said recesses backing for

said web-section comprising material harder than that forming said body, and forcing a matrix-forming punch against said portion to form the matrix cavity therein.

- 5 6. The method of forming matrices which consists in providing a metal matrix body recessed at its back surface to cause the portion in which the matrix cavity is to be formed to comprise a relatively thin web-section, providing, in the 10 recess in said body, backing for said web-section comprising material harder than that forming said body, and forcing a matrix-forming punch against said portion to form the matrix cavity therein.
- 15 7. The method of forming matrices which consists in providing a metal matrix body having a portion integral therewith in which the matrix cavity is to be formed comprising a relatively thin web section, backing said web section with material harder than that forming said body, and 20 forcing a matrix-forming punch against said portion to form the matrix cavity therein.
- 25 8. A matrix blank formed of a body the matrix-cavity portion of which comprises a relatively thin web-section forming a portion only of said body integral therewith, and backing for said web-section formed of material harder than that forming said web-section.
- 30 9. A matrix blank formed of a body recessed between its upper and lower surfaces adjacent its matrix-cavity portion to cause said portion to comprise a relatively thin web-section and backing in said recess for said web-section formed of material harder than that forming said web-section.
- 35 10. A matrix blank formed of a body having substantially parallel recesses between its upper and lower surfaces adjacent its matrix-cavity portion to cause said portion to comprise a relatively thin web section, and backing in said 40

recesses for said web section formed of material harder than that forming said web section.

11. A matrix blank formed of a body recessed at its back surface to cause its matrix cavity portion to comprise a relatively thin web-section and backing in said recess for said web-section formed of material harder than that forming said web-section. 5

12. A matrix the body, including the matrix-cavity forming portion, of which is formed integrally of one kind of metal, said portion comprising a relatively thin web-section, and backing for and substantially coextensive with said web-section formed of material harder than that forming said web-section. 10

13. A matrix formed of a body having a relatively thin web section integral therewith and in which the matrix cavity is provided, and backing for and substantially coextensive with said web section formed of material harder than that forming said web section. 15

14. A matrix comprising, in combination, a matrix body formed with a relatively thin portion and having a recess below said portion, said thin portion having a matrix cavity formed therein, and a backing of material harder than that of which said body is formed contained in and completely filling said recess. 20

15. A matrix comprising, in combination, a matrix body having the impression receiving characteristics of brass comprising a relatively thin shell presenting a recess opening at the rear thereof and having a matrix cavity formed therein, and a block of material having the deformation resistant characteristics of steel housed in 30 and contacting substantially the entire surfaces of said recess to form a backing for said matrix cavity carrying portion. 35

ARTHUR H. HEDLY.
